DISTRIBUTING CONTROL DEVICE

Waldemar C. Ewaldson, Millington, N. J., assignor to Western Electric Company, Incorporated, New York, N. Y., a corporation of New York

Application April 5, 1944, Serial No. 529,585

7 Claims. (Cl. 242—4)

This invention relates to a distributing control device, particularly for toroidal coil winding apparatus.

In the manufacture of toroidal coils, the wires to be wound upon the cores thereof are required to be of given diameters within fine limits, but the existence of variations in the diameters of the wires, although small, may cause variations in the locations of the outer convolutions of the wires on the cores. It is important that these outer convolutions lie closely adjacent so that during the finishing operations of the coils, the outer convolutions will form a substantially continuous surface.

An object of the invention is to provide a distributor for winding apparatus which is simple in structure and highly variable to compensate for variations in the size of material being distributed.

With this and other objects in view, the invention comprises a distributing mechanism in a winding apparatus including actuatable means, interposed between the driving means and the work support, to cause variations in the movement of the latter for the laying of closely adjacent convolutions of strand material on the work.

Other objects and advantages will be apparent from the following detailed description when considered in conjunction with the accompanying drawings, wherein

Fig. 1 is a front elevational view of the distributing mechanism shown in a winding apparatus;

Fig. 2 is a top plan view of the structure shown in Fig. 1, portions thereof being broken away;

Fig. 3 is an enlarged vertical sectional view of the distributing mechanism, and

Fig. 4 is an enlarged fragmentary detail view taken substantially along the line 4—4 of Fig. 2.

Referring now to the drawings, particularly Figs. 1 and 2, a material serving head is indicated generally at 10 and includes a conventional annular bobbin or material support 11 supported by rollers 12. The rollers 12 are mounted upon spindles 14 carried in bearing portions of one side of a supporting bracket 15. A driving ring 16, having teeth 17 formed in its inner periphery, is supported by a plurality of gears 18 mounted upon spindles 19, the latter being carried in bearing portions of the other side of the bracket 15. A feeding roll or sheave 20, carried by the driving ring 16, receives a wire or strand material 21 from the bobbin 11 and directs it to a core 22 about which the material is wound. The lowermost spindle 19 extends laterally as shown in

Fig. 2, where it is supported by a bearing 25 in a bracket 26 and has a sprocket 27 mounted thereon to be driven by a chain 28 from a suitable power means (not shown). Through the aid of a hand wheel 29, the spindle may be rotated for manually positioning the ring 16 and the bobbin 11 relative to the core 22.

The core 22 is held in a unit 30 which includes a fixed support 31 and a movable clamp 32 actuatable by a threaded element 33 relative to a holding screw 34, to cause clamping of the core or articles between the support 31 and the clamp 32. The unit 30 is mounted upon a flange 35 fixed to or formed integral with a rod 36 which is disposed in a chuck 37. The chuck 37 is mounted upon an element 38, which extends laterally and rests upon a bearing member 39, the latter having a ball race 40 adjacent its periphery for receiving ball-like bearing members 41 positioned to ride upon a companion member 42, the latter being mounted upon a base 43.

A spindle 45 extends vertically through an aperture 46 in the base 43 and is fixed against rotation by the aid of a pin 47. The spindle also extends through apertures in the bearing members 42 and 39 as well as the element 38. A bearing 48 connects the element 38 and the upper bearing member 39 for rotation upon the spindle 45, the element 38 extending to the left of the spindle, as shown in Fig. 3, to support the chuck 37. A plate or supporting bracket 50, of the contour illustrated in Fig. 2, is disposed upon the element 38 and fixed thereto, as at 51. The bracket 50 is also apertured for the spindle 45 and is additionally secured to the element 38 as well as the upper bearing member 39 through the aid of a screw 52. A sleeve 54 is disposed upon the upper end of the spindle 45 for rotation thereon. A worm gear 55 is disposed concentric with the sleeve 54 and secured thereto through the aid of a clamp 56, the sleeve 54 being held against displacement upon the spindle through the aid of lock nuts 57. Another worm gear 58, identical with the gear 55, is disposed therebeneath upon the sleeve 54 and keyed thereto as at 59. A driving shaft 60 (Figs. 1, 2 and 4) is driven by any suitable power means (not shown) in synchronism with the driving means for the chain 28, to cause operation of the serving head 10 to serve the material 21 at a given rate upon the core 22 during movement of the core for the distribution of the material thereon. A worm 62, mounted upon the shaft 60 and driven thereby, interengages the worm gear 55 to cause rotation thereof.

The bracket 50 has a bearing member 63 mounted thereon for rotatably supporting a shaft 64 (Fig. 4). A worm 65 is fixedly mounted upon the shaft 64 and interengages the worm gear 58. A bevelled gear 66, fixedly mounted upon the other end of the shaft 64, interengages a similar bevelled gear 67 which is mounted upon one end of a shaft 68, the latter being journalled in a bearing 69 of a bracket 70. The bracket 70 is fixedly mounted, as at 71, upon the bracket 50. A hand wheel 72 is fixedly mounted upon the other end of the shaft 68 for manual rotation of the shaft.

Upon considering the operation of the apparatus, let it be assumed that the bobbin 11 is filled with the desired amount of material 21, which in the present instance is an insulated wire of a suitable conductive material, and that the article, namely the core 22, is supported in the work holder or unit 30. If the diameter of the insulated wire is of a given diameter, the driving mechanism (not shown) for the shaft 60 and the chain 28 is adjusted so that if the material throughout its length is of the given diameter, the core will be moved at a speed relative to the head 10 so that each portion of each convolution of the wire upon the outer periphery of the core will be in close engagement with each other. The distributing mechanism is such that during the travel of the rotating portions, namely the bobbin 11 and the driving ring 16, through one complete cycle, the core will be moved the given distance about the spindle 45, the axis of which is at the center line of the article. This movement is brought about through the rotation of the shaft 60 to rotate the worm gear 55 through its worm 62, to rotate the sleeve 54 and with it the worm gear 58. The worm 65, unless rotated, that is, in its normal inactive position, provides a positive connection between the worm gear 58 and the bracket 50, causing the bracket, together with the element 38 and the unit 30 supported thereby, with the article or core 22, to move at a given rate of speed about the spindle 45.

The laying of the material on the core is observed by the operator, and if the outer portions of the convolutions should tend to pile up, the operator may instantly vary the position of the article with respect to the serving head through the rotation of the hand wheel 72, its shaft 68, and, through the aid of the bevelled gears 67 and 66, to cause rotation of the worm 65 to advance the movement of the unit 30 to eliminate the existence of this condition. If the portions of the outer convolutions of the material should appear to be spaced apart and not disposed closely adjacent, the movement of the unit 30 with the core or article 22 may be retarded by movement of the hand wheel 72 in the opposite direction to move the unit 30 with the article relative to the worm gear 58 so that these convolutions will be more closely positioned with respect to each other. All of these variations may be brought about without stopping the operation of the apparatus or without varying the setting thereof for the type of material or wire being employed. As previously described, the material or insulated wire must be of a given diameter within certain limits, these limits being, for example, plus or minus .003 of an inch. These limits are very small, but it is apparent that if the dimensions of the wire should include one or the other of these limits, the multiplication of these limits over several convolutions of the material would eventually cause them to pile up or to be spaced apart. This is overcome through the aid of the varying means em-

bodied in the distributing mechanism of the apparatus.

Although specific improvements of the invention have been shown and described, it will be understood that they are but illustrative and that various modifications may be made therein without departing from the scope and spirit of this invention as defined by the appended claims.

What is claimed is:

- 10 1. In an apparatus for winding material on a circular article including a unit to support the article and a rotatable serving head for the material, driving means to rotate the serving head at a constant speed to cause laying of convolutions of the material on the article, means to support the unit for rotary movement about an axis in alignment with the center line of the article, a variable element carried by the unit, a member operatively connected to the element and rotatable about the axis, driving means operable in synchronism with the driving means for the serving head and including the element and the member to move the unit and the article about the said axis and center line to cause the portions of the convolutions of the material at the outer periphery of the article to successively lay at predetermined positions relative to each other, and means to actuate the element to vary the said driving means for the unit to vary the said positions of the portions of the material while the speed of the serving head remains constant.
- 15 2. In an apparatus for winding material on a circular article including a unit to support the article and a rotatable serving head for the material, driving means to rotate the serving head at a constant speed to cause laying of convolutions of the material on the article, means to support the unit for rotary movement about an axis in alignment with the center line of the article, a variable element carried by the unit, a member operatively connected to the element and rotatable about the axis, driving means operable in synchronism with the driving means for the serving head and including the element and the member to move the unit and the article about the said axis and center line to cause the portions of the convolutions of the material at the outer periphery of the article to successively lay at predetermined positions relative to each other, and means to actuate the element relative to the member to retard the said driving means for the unit to cause positioning of the said portions of the material closer together while the speed of the serving head remains constant.
- 20 3. In an apparatus for winding material on a circular article including a unit to support the article and a rotatable serving head for the material, driving means to rotate the serving head at a constant speed to cause laying of convolutions of the material on the article, means to support the unit for rotary movement about an axis in alignment with the center line of the article, a variable element carried by the unit, a member operatively connected to the element and rotatable about the axis, driving means operable in synchronism with the driving means for the serving head and including the element and the member to move the unit and the article about the said axis and center line to cause the portions of the convolutions of the material at the outer periphery of the article to successively lay at predetermined positions relative to each other, and means to actuate the element relative to the member to retard the said driving means for the unit to cause positioning of the said portions of the material closer together while the speed of the serving head remains constant.
- 25 4. In an apparatus for winding material on a circular article including a unit to support the article and a rotatable serving head for the material, driving means to rotate the serving head at a constant speed to cause laying of convolutions of the material on the article, means to support the unit for rotary movement about an axis in alignment with the center line of the article, a variable element carried by the unit, a member operatively connected to the element and rotatable about the axis, driving means operable in synchronism with the driving means for the serving head and including the element and the member to move the unit and the article about the said axis and center line to cause the portions of the convolutions of the material at the outer periphery of the article to successively lay at predetermined positions relative to each other, and means to actuate the element relative to the member to retard the said driving means for the unit to cause positioning of the said portions of the material closer together while the speed of the serving head remains constant.
- 30 5. In an apparatus for winding material on a circular article including a unit to support the article and a rotatable serving head for the material, driving means to rotate the serving head at a constant speed to cause laying of convolutions of the material on the article, means to support the unit for rotary movement about an axis in alignment with the center line of the article, a variable element carried by the unit, a member operatively connected to the element and rotatable about the axis, driving means operable in synchronism with the driving means for the serving head and including the element and the member to move the unit and the article about the said axis and center line to cause the portions of the convolutions of the material at the outer periphery of the article to successively lay at predetermined positions relative to each other, and means to actuate the element relative to the member to increase the speed of movement of the

unit to cause positioning of the said portions of the material at more widely spaced positions while the speed of the serving head remains constant.

4. In an apparatus for winding material on a circular article including a unit to support the article and a rotatable serving head for the material, driving means to rotate the serving head at a constant speed to cause laying of convolutions of the material on the article, means to support the unit for rotary movement about an axis in alignment with the center line of the article, a member rotated on the axis at a constant speed, a variable element operatively connecting the member to the unit to normally cause rotation of the unit and the article at the same speed as the member is rotated, means to rotate the member, and means to actuate the element relative to the member to vary the speed of the unit to vary the laying of the convolutions of the material on the article while the speed of the serving head remains constant.

5. In an apparatus for winding material on a circular article including a unit to support the article and a rotatable serving head for the material, driving means to rotate the serving head at a constant speed to cause laying of convolutions of the material on the article, means to support the unit for rotary movement about an axis in alignment with the center line of the article, a member rotated on the axis at a constant speed, a variable element operatively connecting the member to the unit to normally cause rotation of the unit and the article at the same speed as the member is rotated, means to rotate the member, and means to actuate the element relative to the member to retard the speed of the unit to cause positioning of the convolutions of the ma-

terial closer together on the article while the speed of the serving head remains constant.

6. In an apparatus for winding material on a circular article including a unit to support the article and a rotatable serving head for the material, driving means to rotate the serving head at a constant speed to cause laying of convolutions of the material on the article, means to support the unit for rotary movement about an axis 10 in alignment with the center line of the article, a member rotated on the axis at a constant speed, a variable element operatively connecting the member to the unit to normally cause rotation of the unit and the article at the same speed as the member is rotated, means to rotate the member, and means to actuate the element relative to the member to increase the speed of the units to cause positioning of the convolutions of the material farther apart on the article while the speed of the serving head remains constant.

7. In an apparatus for winding material on a circular article including a unit to support the article and a rotatable serving head for the material, driving means to rotate the serving head at a constant speed to cause laying of convolutions of the material on the article, means to support the unit for rotary movement about an axis in alignment with the center line of the article, a worm gear rotated on the axis at a constant speed, a worm operatively connecting the worm gear to the unit to normally cause rotation of the unit and the article at the same speed as the gear is rotated, means to rotate the gear, and means to rotate the worm to vary the speed of rotation of the unit to vary the laying of the convolutions of the material on the article while the speed of the serving head remains constant.

WALDEMAR C. EWALDSOHN.
